FREE-STANDING FIREPLACE

Trace Christenson, Jr., and Robert L. Gallup, Niles,
Mich., assignors to The Majestic Company, Inc., Huntington,
Ind., a corporation

Filed Mar. 17, 1960, Ser. No. 59,774

Term of patent 14 years

(Cl. D81—7)

The figure is a perspective view of a free-standing fireplace, showing our new design.

The two undisclosed sides of the free-standing fireplace and of the chimney element are, respectively, the same in appearance as the two sides shown.

We claim:

The ornamental design for a free-standing fireplace, as shown and described.
